UNITED STATES PATENT OFFICE.

JAMES M. CHATFIELD AND KARL W. HALDEN, OF THOMASTON, CONNECTICUT.

MACHINE FOR OVERHAULING METAL.

1,051,084.

Specification of Letters Patent. Patented Jan. 21, 1913.

Application filed January 26, 1912. Serial No. 673,615.

To all whom it may concern:

Be it known that we, JAMES M. CHATFIELD and KARL W. HALDEN, citizens of the United States, residing at Thomaston, in 5 the county of Litchfield and State of Connecticut, have invented a new and useful Improvement in Machines for Overhauling Metal; and we do hereby declare the following, when taken in connection with the accompanying drawings and the characters of reference marked thereon, to be a full, clear, and exact description of the same, and which said drawings constitute part of this specification, and represent, in—

15 Figure 1 a top or plan view of an overhauling machine constructed in accordance with our invention, and illustrating mechanism by which our method may be carried out. Fig. 2 a side view of the same. Fig. 20 20 3 a view in front end elevation. Fig. 4 a central longitudinal sectional view. Fig. 5 a transverse sectional view with the trunnion blocks and transmission shown in side elevation. Fig. 6 a reverse broken plan 25 view of the bed of the machine. Fig. 7 a longitudinal sectional view through one of the trunnion blocks showing the spindle and guide enlarged. Fig. 8 a side view of one of the cutter-heads removed. Fig. 9 a face 30 view of the same partially in section. Fig. 10 a top or plan view of one of the brackets showing spring boxes therein with the gears removed. Fig. 11 a side view partly in section of the same. Fig. 12 a top or plan view 35 of one of the brackets with the box and rolls removed. Fig. 13 an end view of the same. Fig. 14 a broken view on an enlarged scale, showing the relative position of the cutters.

This invention relates to an improvement 40 in machines for overhauling flat metal plates, that is, for removing the scale or oxidation from plates of brass after they come from a rolling mill. Machines for this purpose are sometimes called scalping machines.

The object of this invention is to provide means for supporting the plates on one edge and for scalping the entire surface of one or both sides of a strip of metal at one operation rather than to scalp or trim a portion of one surface and then subsequently complete the operation by scalping or cleaning the remaining surface of that side; and the invention consists in the method and 55 construction hereinafter described and particularly recited in the claims.

In carrying out our invention, the strips of metal as they come from a rolling machine are fed edgewise on a track 2 which extends longitudinally through the machine, resting on the bed 3. The strip thus fed is caught by vertically arranged supporting feed-rolls 4, 5, and is by these feed-rolls moved along to vertical supporting feed-rolls 6 and 7, and thence to vertical supporting feed-rolls 8 and 9, and subsequently to vertical supporting feed-rolls 10 and 11 by which the strip is moved so far beyond the opposite or outer end of the machine as to permit it to be readily grasped and removed 60 from the machine. It will be noted that the several feed-rolls are long rolls so that they form supports for the strip being fed through the machine, as distinguished from disk-like rolls which have merely the function of feed-rolls. The rolls 4 and 6 are carried in a bracket 12, the rolls 5 and 7 in a similar bracket 13, the rolls 7 and 10 by a bracket 14, and the rolls 9 and 11 by a bracket 15. These brackets are adjustable 65 transversely on the bed toward or from the track 2 and are secured to the bed by bolts 16, and may be moved transversely by screws 17 mounted in uprights 18 at opposite sides of the bed, which uprights are connected by 70 a tie-rod 88, the screws being held against longitudinal movement, but free to turn in the uprights and having threading engagement with the brackets. Below the bed 3 are two transversely arranged shafts 19 and 80 20. Keyed to one of these shafts, as 19, are three worms 21, 22 and 23, and to the other shaft 20 are three similar worms 24, 25 and 26, the worms on one shaft being reversed 85 in pitch to the worms on the other shaft. 90 The lower end of the feed-roll 5 carries a worm-gear 27 which meshes with the worm 22 by which it is driven in one direction. The feed roll 4 on the other hand carries at its upper end a pinion 28 meshing with a 95 gear 29 on a counter shaft 30 carrying at its lower end a worm wheel 31 which meshes with the worm 23. The feed roll 6 carries at its lower end a worm gear 32 which also 100 meshes with the worm 22, while the feed roll 7 carries at its upper end a gear 33 meshing with a gear 34 on a counter shaft 35 which at its lower end carries a worm gear 36 meshing with the worm 21. The feed roll 8 carries at its lower end a worm gear 37 105 meshing with the worm 25, and the feed roll 9 carries at its upper end a gear 38.

meshing with a gear 39 on a counter shaft 40 having at its lower end a worm gear 41 meshing with the worm 24. The feed roll 11 carries at its lower end a worm gear 42 5 meshing with the worm 25, and the feed roll 10 carries at its upper end a gear 43 meshing with the gear 44 at the upper end of the counter shaft 45 which counter shaft carries at its lower end a worm gear 46 10 meshing with the worm 26, and so that the rolls on one side of the track move in one direction, and the rolls on the opposite side of the track move in the opposite direction and in a direction to carry the strip to be 15 operated upon through the machine.

The sliding movement of the rolls is in a line parallel with the longitudinal axis of the worms, and the length of the threads on the worms is such as to permit the worm 20 gears to be moved with relation thereto without becoming disengaged therefrom.

The ends of the feed rolls 4 and 10 on one side of the track are mounted in sliding boxes 46, 46^a as shown in Fig. 10 and the 25 counter shafts for these rolls are also mounted in sliding boxes 47, 47^a and the boxes 47, 47^a are forced toward the center of the machine by springs 48. The boxes 46, 47, and 46^a, 47^a are connected together by short rods 30 49 serving to maintain them in the same relative position, and keep the gears carried by their upper ends in mesh. The feed rolls 6 and 8 are also forced toward the center of the machine by springs 50 bearing on boxes 35 51, at the ends of these rolls. The boxes 46, 47 and 51 are mounted in recesses 53 formed for them in the tops of the brackets, which recesses limit the inward movement of the boxes. Between the feed rolls 6 and 40 7 and 8 and 9, is a transverse drive shaft 54; and mounted on the bed below this shaft are two trunnion blocks 55 and 56. The trunnion blocks 55 and 56 are movable on the bed by set screws 57 and 58, and when adjusted are 45 held by set screws 59 and 60 extending up through slots 61 and 62 in the bed, and the uprights 18 have clearance openings 63 to permit the removal of the trunnion blocks. In the block 55 is a spindle 64, and in the 50 block 56 is a spindle 65. The spindle 64 carries a gear 66 meshing with a pinion 67 on the shaft 54, and the spindle 65 carries a gear 68 meshing with a gear 69 also on the shaft 54, so that these 55 spindles are both driven in the same direction. The spindle 64 carries a ring-like head 70 supporting a series of cutters 71, while the spindle 65 carries a corresponding head 72 with corresponding cutters 73. 60 The cutter heads, as shown, are screwed onto the spindles so that they can be readily removed to allow the cutters to be ground. This is desirable in order to permit one head to be removed and replaced by another, 65 while the cutters in the removed head are

being ground. The spindles 64 and 65 are suitably mounted in the trunnion blocks and are tubular, and extending through them are rod-like guide-carriers 74 each carrying at its inner end a disk-like guide 75 which guides stand within the circle described by the cutters. These guide-rods are held against rotation in the spindle by keys 76, and are permitted to have the slight longitudinal movement necessary for adjustment. The outer ends 77 of these guide-rods are reduced in diameter to receive nuts 78, and are held in place on the reduced end 77 by washers 79. These guides serve to support the strip at the time it is being cut and prevent the strip from moving transversely so that one cutter will not cut deeper than the other, and also for supporting the forward end of the strip as it enters between the cutters, and for supporting the rear end of the strip as it leaves the cutters. In other words, the guides serve to hold the strip centrally between the cutters. It may be noted that the spindles have flanges 80 bearing against the inner ends of the trunnion blocks and carry nuts 81 at their outer ends, whereby they are held against longitudinal movement. The drive shaft 54 is connected through any suitable change-speed mechanism with a shaft 82 which 85 shaft carries sprocket wheels 83, 83^a and these sprocket wheels are connected by sprocket chains 84 and 85 with the worm shafts 19 and 20. The bearings for the drive shaft 54 are in the uprights 18, and the 90 bearing for the shaft 82 is in one of the uprights 18 which upright also carries a yoke 86 supporting a box 87 for one end of the shaft 82.

A strip of brass coming from the rolling mill is fed onto the track 2 and is caught by the feed rolls 4 and 5 and by them carried to the feed rolls 6 and 7. By the action of these four rolls and particularly by the rolls 6 and 7, the strip is forced between the cutters where the entire surface of both sides of the strip is overhauled or scalped, and it will be noted that the movement of the cutters gives a sweeping cut and the direction is downward tending to throw the chips 115 downward through the bed of the machine which is open below the cutters so that all chips may immediately drop out, and therefore cannot by any possibility clog the machine or interfere with the action of the cutters, which in their upward movement clear the strip and prevent undue cutting or scratching after the surface has been finished.

It is apparent, without illustration, that if 125 desired, the cutters on one of the spindles might be omitted and the strip first scalped on one side and then passed through the machine so as to scalp or overhauled the opposite side. But preferably both sides will be 130

scalped at a single operation. It is also obvious that instead of mounting the spindles exactly in line with each other, they might be arranged parallel with each other but in different planes so that the cutting on one side of the strip would take place in advance of the cutting on the opposite side of the strip. As a matter of fact, the spindles are not exactly in line but so nearly so, 10 that it is impossible to illustrate the offset, on the scale shown. In Fig. 14, however, this offset is shown on an exaggerated scale. This offset, although very slight, is sufficient to make the space between them 15 slightly less at the front than at the back, and this is to insure the cutters clearing the metal after the metal has been overhauled or scalped.

We claim:—

- 20 1. In a machine for overhauling flat metal bars, the combination with a bed, of a longitudinal track thereon, brackets arranged on opposite sides of the track, and transversely adjustable, vertically arranged feed-rolls 25 mounted in said brackets, spindles mounted on opposite sides of the track, said spindles carrying ring-like cutters, guide-rods extending through said spindles and carrying

guides within the circle described by the cutters, means for adjusting the guides and cutters, and means for driving the cutters. 30

2. In a machine for overhauling flat metal bars, the combination with the bed thereof, of a longitudinal track across the bed, trunnion bearings arranged on opposite sides of the track, spindles mounted in said trunnions and carrying cutter-heads, cutters mounted in said heads, brackets mounted on said bed on opposite sides of the track, said brackets carrying vertically arranged feed 35 rolls, a drive shaft in connection with the spindles whereby the cutters are revolved, worm shafts arranged below the bed and carrying worms having connection with the feed rolls, and connections between the drive 40 shaft and worm shafts whereby the cutters and feed rolls are moved in unison. 45

In testimony whereof, we have signed this specification in the presence of two subscribing witnesses:

JAS. M. CHATFIELD.
KARL W. HALLDEN.
